CONTROL MECHANISM FOR RADIO APPARATUS

Filed July 16, 1930

INVENTOR.
Joseph Mendola,
BY John O. Brady
ATTORNEY

UNITED STATES PATENT OFFICE

JOSEPH MENDOLA, OF ROCHESTER, NEW YORK

CONTROL MECHANISM FOR RADIO APPARATUS

Application filed July 16, 1930. Serial No. 468,402.

My invention relates broadly to radio apparatus and more particularly to a control mechanism for radio apparatus.

One of the objects of my invention is to provide means for controlling the adjustment of the tuning mechanism in a radio system.

Another object of my invention is to provide a construction of control mechanism for radio apparatus having means for limiting the adjustment within predetermined controllable limits.

Still another object of my invention is to provide a construction of control mechanism for radio apparatus including a belt driving system having adjustable means for limiting the extreme movement of the control mechanism for preventing strain upon the belt driving system.

20 A further object of my invention is to provide an attachment for a control mechanism and a belt driving system in which strain on the belt may be relieved by predetermining the position at which movement of the control is brought to a stop.

A still further object of my invention is to provide an adjustable stop mechanism adapted to be applied to standard forms of instrument control for actuating a driving belt 25 within predetermined limits while preventing undue strain upon the belt.

Other and further objects of my invention reside in the construction of protective device for insuring the efficient operation of the control mechanism of an electrical tuning apparatus as set forth more fully in the specification hereinafter following by reference to the accompanying drawings, in which:

Figure 1 is a side elevation of an indicator drum and pulley showing the control means of my invention associated therewith for the annular movement of the control shaft connected with the indicator drum; Fig. 2 is a front elevation of a tuning condenser and control shaft coupled thereto with the attachment of my invention applied thereto; Fig. 3 is a side elevation on an enlarged scale of the limiting stop arrangement of my invention applied to the control shaft; Fig. 4 is a cross-sectional view taken through the parts of the

limiting stop mechanism and control shaft with parts illustrated in side elevation; Fig. 5 is a fragmentary view taken partially in cross-section on line 5-5 of Fig. 4; Fig. 6 is a cross-sectional view taken on line 6-6 of Fig. 4; Fig. 7 is a cross-sectional view taken through the position limiting device of my invention on line 7-7 of Fig. 4; and Fig. 8 is a perspective view illustrating the arrangement of the several parts of the position limiting device of my invention.

My invention is particularly adaptable for radio receiver apparatus in relieving undue strain on the driving cord or belt in an adjustable tuning mechanism. Heretofore in constructions of tuning control mechanism employing a driving belt difficulty has been experienced due to slackness occurring in the drive belt resulting in slippage of the control and impairing the operation of the receiver. In the operation of a radio broadcast receiver in the home it is not unusual for the tuning control to receive considerable mistreatment. That is, the tuning control may be carelessly rotated back and forth and torsional stress applied to twist the tuning control beyond the normal stop so often that the drive cord is stretched or broken and thereafter tends to jump away from the pulley and no longer functions to impart accurate movement to the shaft of the tuning apparatus. As a result of undue stretching the cord or belt merely slips around the drive pulley and it is no longer possible to control the tuning apparatus.

By my invention I provide means for predetermining the position of limiting stops at each extreme in the arc of movement of the control shaft for preventing undue strain on the driving cord or belt and thereby accurately preserving the adjustment of the tuning mechanism. The predetermining position stop mechanism of my invention may be readily applied to standard forms of belt drive in the tuning controls of radio apparatus. The construction of the parts of the predetermining position mechanism is such that they may be readily mounted with respect to the control shaft of the tuning mechanism.

Referring to the drawings in detail, reference character 1 indicates the adjustable shaft of a tuning apparatus such as a multiple unit **gang condenser** 3, including sets of stator and rotor plates indicated at 3a, 3b, 3c, and 3d respectively. An indicator drum 2 is mounted on the indicator control shaft 1 and has pulleys 4 immediately adjacent thereto over which the drive cords 5 are looped. The drive cords 5 may be secured as indicated on the pulleys 4 as at 12 and secured at their extremities to the peripheral spirally grooved drums 14 and 15 grooved for the reception of drive cords. The drums 14 and 15 are rigidly carried by shaft 18. The drum 14 is rigidly secured to shaft 8 by a set screw 14a which enters a preformed socket 8a in shaft 8. The drum 15 may be similarly secured to shaft 8 by means of set screw 15a which extends into the preformed socket 8b in shaft 8. The shaft 8 is journaled in bearings provided in the upturned ends 16 of the yoke 10. The yoke 10 is mounted upon the base plate 11 of the condenser chassis by means of screw members indicated at 11a and 11b. The control shaft 8 is adapted to receive a sleeve member 17 exteriorly screw threaded throughout a portion of its length. The sleeve 17 is firmly secured to the shaft 8 by means of set screw 19 which extends into a preformed socket 8c in the control shaft 8 thereby rigidly maintaining the sleeve 17 in position on shaft 8 in such manner that the sleeve 17 rotates with the movement of control shaft 8 which is in turn controlled from externally extending shaft 9. A carriage 20 is internally screw threaded to receive the screw threads 18 of the sleeve 17 and is provided with a radially projecting pin 21 screw threaded therein which pin is adapted to move longitudinally in a slot 22 formed in the yoke 10. The slot 22 in the yoke 10 has such a length as is necessary to predetermine the limits of movement of the control shaft 8. The pin 21 abuts against the end of the slot 22 in the course of the driving movement effected by rotation of the shaft 8 and screw threaded sleeve 17 attached thereto and engaging the interior screw threads in the carriage 20. This abutment provides a positive stop for the shaft 8 and prevents further pull on cord 5. The same limit of rotation may be obtained at the opposite limit of movement of the indicator drum by abutment of pin 21 against the opposite end of slot 22. It is understood that the movement of the indicator drum and associated tuning apparatus is substantially 180° so that the slot 22 is formed of such size that full movement of the indicator drum and associated tuning apparatus is obtained without introducing undue stress and strain upon the cord or belt 5. Where it is desired to reduce the path of travel of the carriage 20 I provide an adjustable member 23 in the form of a strip having

an upturned edge 24 which may be advanced or retracted with respect to the path of movement of the carriage 20. The end of the adjustable member 23 is bifurcated as indicated at 25 for the passage of a screw member 26 therethrough. The screw member 26 extends upwardly through plate 11 and yoke 10 and has an adjustable nut 27 thereon. The adjustable member 23 has a cylindrical aperture 23a therein in which the eccentric 28 is located. An adjusting screw 29 extends upwardly through plate 11 and yoke 10 into the eccentric 28 enabling adjustment of the eccentric to be made for the advancement or retraction of strip member 23 along yoke 10. By moving the upstanding end 24 of strip 23 into the path of carriage 20 the limit of rotation of control shaft 8 may be further reduced thus preventing undue strain on the cord or belt 5.

The adjustable member 23 is necessary in predetermining the stop position of the control shaft 8 due to inaccuracies in manufacture and stretching of the cord or belt 5. From time to time the strip member 23 may be adjusted to compensate for stretching of the drive cords under operation or temperature influences.

Due to the simplicity of the predetermining position stop device of my invention, the device of my invention may be readily applied to tuning mechanism of standard types. I have found that the device of my invention increases the ability of the tuning condenser to withstand shock movement brought about by excess forces applied in either a clockwise or counterclockwise direction upon the control knob. The accuracy of the apparatus may thus be maintained and the receiver tuning control rendered substantially safe even in the hands of an unskilled operator.

While I have described my invention in certain preferred embodiments I desire that it be understood that modifications may be made and that no limitations upon my invention are intended other than are imposed by the scope of the appended claims.

What I claim as new and desire to secure by Letters Patent of the United States is as follows:

1. An electrical tuning apparatus comprising a rotatable instrument shaft, a pulley carried by said shaft, a control shaft extending normal to said rotatable instrument shaft, a drive cord looped over said pulley and operative by movement of said control shaft to impart angular movement to said rotatable instrument shaft, an externally screw threaded sleeve concentrically secured to said control shaft, a longitudinally movable carriage shiftable along said externally screw threaded sleeve, a member projecting from said carriage in the path of predetermined position stops, and an adjustable stop adjacent one of the limiting stops for limiting the travel

of said movable carriage in one direction, whereby the rotation of said instrument shaft beyond predetermined limits is prevented and strain upon said drive cord eliminated.

5 2. In a control apparatus, a rotatable shaft, an externally screw threaded sleeve member carried by said shaft, a screw threaded carriage engaging said sleeve member, a pin on said carriage projectible into the path of predetermined positioned stops, and an adjustable stop adjacent one of the limits of travel of said carriage for preventing the movement of said carriage beyond a predetermined position while permitting the angular adjustment of said control shaft within predetermined limits.

10 3. A control apparatus comprising a frame structure, a rotatable control shaft journaled in said frame structure, an externally screw threaded sleeve on said control shaft, a screw threaded carriage engaging said externally screw threaded sleeve, a pin on said carriage projecting into a slot in said frame structure for predetermining the limits of travel of said carriage, and a member movable with respect to said frame structure into the path of said carriage for limiting the travel of said carriage and correspondingly predetermining the limits of rotation of said control shaft.

15 4. A control apparatus comprising a frame structure, a rotatable control shaft journaled in said frame structure, an externally screw threaded sleeve on said control shaft, a screw threaded carriage engaging said externally screw threaded sleeve, a pin on said carriage projecting into a slot in said frame structure for predetermining the limits of travel of said carriage, a member carried by said frame structure in alignment with said movable carriage and adjacent said slot, and an eccentric operative through said frame structure for advancing or retracting said member in the path of said carriage for adjustably defining the limit of travel thereof, whereby the 20 rotation of said control shaft may be correspondingly limited.

In testimony whereof I affix my signature.
JOSEPH MENDOLA.
